CONTACT SCREW

Filed April 1, 1927

INVENTOR

R.H.WILLIAMS
BY *Munn & Leo*

ATTORNEYS

UNITED STATES PATENT OFFICE.

ROY HERRMAN WILLIAMS, OF EVANSVILLE, INDIANA.

CONTACT SCREW.

Application filed April 1, 1927. Serial No. 180,205.

My invention relates to improvements in contact screws, and it consists in the combinations, constructions, and arrangements herein described and claimed.

5 An object of my invention is to provide a contact screw which may be readily applied to any fuse plug receptacle.

10 A further object of my invention is to provide a device of the type described which contains a concealed fuse for a novel purpose. There are many instances where a person not desiring to purchase a new fuse plug or replace the fuse plug when blown resorts to the placing of a penny or a metal strip between 15 the lower or central contact of the fuse plug and the central contact member of the fuse plug receptacle for securing a continued supply of current.

15 A further object of my invention is to provide a device of the type described which is simple in construction, and efficient for the purpose intended.

20 Other objects and advantages will appear in the following specification, and the novel features of the invention will be particularly pointed out in the appended claims.

25 My invention is illustrated in the accompanying drawings, forming part of this application, in which

30 Figure 1 is a side elevation of the device as applied to a fuse block or receptacle,

Figure 2 is a sectional view of my device, a portion thereof being shown in elevation,

35 Figure 3 is a section along the line 3—3 of Figure 2, and

Figure 4 is a section along the line 4—4 of Figure 2.

40 In carrying out my invention, I make use of the ordinary type of fuse block 1, such as found in the standard house lighting circuit. This block 1 has a receptacle portion 2 of insulating material formed integral with the block 1. A contact shell 3 is provided with rolled threads adapted to receive a threaded 45 portion of a fuse plug 4. The fuse plug 4 is provided with a fuse 5 extending from a contact point 6 to a metallic casing 7. A terminal post 8 is electrically connected to the shell 3. A terminal post 9 is electrically connected to 50 a strip 10 which extends beyond the center of the block 1.

I provide a contact screw which consists of a body portion 11, a cover 12, a threaded shank 13, a contact point 14, and a fuse wire 15.

55 The body portion 11 and the cover 12 are discs formed of any suitable insulating material

and provided with aligned recesses 16 and 16^a, respectively. The threaded shank 13 is provided with integral projections 17 which are receivable in the recesses 16 and 16^a. De- 60 pressed portions 18 and 19 are provided in the body portion 11 and the cover 12, respectively, for forming a fuse-receiving compartment when the body portion 11 and cover 12 are in their assembled position. The fuse wire 15 65 is substantially U-shaped and disposed in the compartment in such a manner that one end thereof is rigidly secured to the threaded shank 13, and the other end rigidly secured to the contact point 14. The body portion 11 and 70 the cover 12 may be secured together by any suitable means not shown.

75 From the foregoing description of the various parts of the device, the operation thereof may be readily understood. The threaded shank 13 may be screwed into the block 1 and into the strip or conductor 10. In this manner, the contact screw may be removed from the front of the block. This may be prevented however if so desired by placing a lock nut 80 20 upon the end of the threaded shank 13 adjacent the strip 10. The fuse plug 4 is then disposed in the shell 3, the contact point 6 engaging with the contact point 14.

85 Let us assume that the fuse 5 of the fuse plug 4 burns out. In this manner, the electric circuit is broken. The user by placing a coin or a metal strip between the contact points 6 and 14 and in connection with the metal shell 3 may again close the circuit. However, in 90 case of high amperage, the fuse wire 15 which is slightly larger and more durable than the fuse 5 will burn out.

I claim:

1. The combination with a fuse block having a fuse receptacle, a contact shell disposed in said receptacle, a terminal post in electrical connection with said contact shell, a second terminal post, a fuse plug having a metallic casing receivable in the contact shell, a central contact point, and a fuse connecting said metallic casing with said central contact point, of a contact screw adapted to be disposed in said contact shell and in engagement with said central contact point, said contact screw being in electrical connection with said second named terminal post, and fusible means carried by said contact screw for breaking the circuit between said contact shell and said second named terminal post. 110

2. A device of the type described comprising a threaded shank receivable in a fuse

plug receptacle, a body portion, a cover, a central contact point carried by said cover, and means for electrically connecting said central contact point with said threaded shank.

3. A device of the type described comprising a body portion having recesses and a groove therein, a cover having recesses and a groove therein adapted to align with the 10 recesses and groove of said body portion, a threaded shank, lugs integral with said threaded shank and receivable in said recesses, a central contact point carried by said cover, and a fuse wire electrically connected 15 to said central contact point and said threaded shank, said groove in said body portion and said cover forming a compartment for receiving said fuse wire.

4. A device of the type described comprising 20 a pair of insulating members having

grooves therein forming compartments, a contact point carried by one of said insulating members, a threaded shank extending through the other of said insulating members, a projection integral with said shank 25 and receivable in one of said compartments, and means for connecting said contact point with said shank.

5. A device of the type described comprising a pair of insulating members having 30 grooves therein forming compartments, a contact point carried by one of said insulating members, a threaded shank extending through the other of said insulating members, a projection integral with said shank 35 and receivable in one of said compartments, and fusible means for connecting said contact point with said shank.

ROY HERRMAN WILLIAMS.
